Specification for Design.

Patented Aug. 11, 1914.

Application filed February 19, 1914. Serial No. 819,846. Term of patent 14 years.

To all whom it may concern:

Be it known that I, CARL A. MEILICKE, a subject of the King of Great Britain, residing at Chicago, in the county of Cook and State of Illinois, have invented a new, original, and ornamental Design for a Calculating-Machine Casing, of which the following is a specification, reference being had to the accompanying drawing, wherein I have shown my design.

Figure 1 is a perspective view, and Fig. 2 an end elevation, of a calculating machine casing showing my new design.

I claim:

The ornamental design for a calculating machine casing, as shown.

CARL A. MEILICKE.
